Specification for Design.

Patented Feb. 17, 1914.

Application filed November 17, 1913. Serial No. 801,541. Term of patent 14 years.

To all whom it may concern:

Be it known that I, SANFORD S. VAUGHAN, a citizen of the United States, residing at the village of Oak Park, in the county of Cook and State of Illinois, have invented a new, original, and ornamental Design for Wood-Chisels, of which the following is a specification, reference being had to the accompanying drawings, forming part thereof.

In these drawings Figure 1 is a face view

of a wood chisel showing my new design; and Fig. 2 is a side view of the chisel shown in Fig. 1.

I claim:

The ornamental design for a wood chisel, substantially as shown.

SANFORD S. VAUGHAN.
